UNITED STATES PATENT OFFICE.

JOHN J. HALDEMAN, OF SUNBURY, PENNSYLVANIA.

POLISHING-MACHINE.

1,359,364.

Specification of Letters Patent. Patented Nov. 16, 1920.

Application filed October 14, 1918. Serial No. 257,970.

To all whom it may concern:

Be it known that I, JOHN J. HALDEMAN, a citizen of the United States, residing at Sunbury, in the county of Northumberland and State of Pennsylvania, have invented certain new and useful Improvements in Polishing-Machines, of which the following is a specification.

This invention relates to polishing machines, and more especially to machines for polishing reeds for weaving machines, and has for its object the more rapid and efficient means for polishing reeds than can be done by hand.

The various features of the invention will be more fully described in connection with the accompanying drawing in which:

Figure 1 is a side elevation of the polishing machine and support for the same.

Fig. 2 is a top plan view of the same.

Fig. 3 is a sectional view of the guiding means for connecting rods.

Fig. 4 is a top plan view of the polisher holder.

Fig. 5 is a side elevation of a polisher holder.

Fig. 6 is a side elevation of the means for raising the reciprocating rods.

Referring to the drawings, 1 indicates a bench or other supporting device for the polishing machine. 2 indicates a stand adapted to support a main power shaft 3. Mounted on said shaft 3 are gears 4 adapted to engage and drive a second pair of gears 5 mounted on a shaft 6. Driving rods 7-7' are pivotally connected to gears 5 on opposite sides of shaft 6, by means of crank pins 8 in slots 9 the length of the stroke of said driving rods is regulated by the adjustment of the crank pins in said slot 9. By the above arrangement it will be seen that the driving shafts are alternately reciprocated in opposite directions. Two connecting rods 10-10' sliding horizontally in guide ways 11 in boxes 12 are pivotally connected to driving rods 7-7' at 13-13' and to reciprocating rods 14-14' at 15-15' 16-16' indicate connections for spring 17, said spring exerting a downward or pulling influence on the said rods 14-14'. 18 indicates an opening in the bench top through which spring 17 passes.

In standards 19 are secured trunnions 20, one of which is shown in Fig. 6, and journaled on said trunnions are two similar eccentrics 21, connected by a part 21^a, to which

is attached a lever 24. Rotatably mounted on the eccentrics are spool shaped cylinders 22, 22', the flanges 23, 23' of these cylinders forming guides for the reciprocating rods 14-14', which rest upon said cylinders. The lever 24 operates in a sector-shaped guideway 25, said guideway having a series of holes 26, in which pins may be inserted to hold the lever in any desired position of adjustment. The purpose of said lever is to adjust the eccentrics 21, and the cylinders 22, 22' thereon, to raise or lower, at will, the reciprocating rods 14-14' on the ends of which are mounted polisher holders 27-27'. The said polisher holders are provided with V-shaped arms 28-28' into which loosely fit the rods 14-14' (Fig. 5) and they are held in place by means of bolts 29 and 30. Small spiral springs 31 encircling said bolts 29 are interposed between the inner sides of the arms 28-28' and reciprocating rods 14-14'. Abrasive blocks 32 are held in the retainers 27, 27' by means of bowed spring keepers 33 and thumb screws 34, the keepers bearing against the polishing blocks at the edges of the latter only, to prevent breakage of the same. Bolts 35 pass through each side of the holders 27 having small spiral springs 36 encircling them and interposed between the inner face 37 of the said holder 27 and the keeper 33. The object of the said spring 36 is to release the keeper 33 when the thumb screw 34 is loosened. The reed 38 to be polished is held in place by means of clamps 39 which are adjustable by means of screw 40 which has a right and left thread. A carriage 41 which holds the clamps 39 can be moved forward and backward by means of screw 42. A lug 43 on screw 40 is held permanently in place by means of set screw 44, and its object is to limit the movement of the screw 40. The purpose of the movable carriage is to accommodate abrasive blocks of varying thickness. The object of having the rods 14-14' loosely fitted in the polisher holder 27, and the springs 31 on each of the said rods is to permit of a slight upward and downward motion of the arms 28-28' when the polishing block strikes the sides of the reeds, and thus prevent breakage of any of the parts. By pivoting the driving rods 7-7' in the slots in the gears 5 the stroke of the said driving rods is shortened or lengthened, and reeds of varying widths may be polished.

The drawings show, and only one set of polishers and driving and reciprocating rods are described, but the number is not limited, and any number desired may be 5 used at one time.

The operation of the device is as follows:—The reed to be polished is secured in the clamps by the means described, the abrasive block placed in the center of the 10 reed. The said block is caused to reciprocate over the surface of the reed by means of power from the main shaft exerted through the gears, driving rods, connecting rods, and reciprocating rods. The purpose 15 of the elevating means is to raise the polisher from the reeds in case it is desired to change the same.

What I claim as new and desire to secure by Letters Patent, is:—

20 1. In a polishing machine, the combination with a holder for the article to be polished, of a horizontally movable rod, a holder for abrasive material attached to said rod, and means for supporting said rod and 25 adjusting it vertically comprising an eccentric, a lever for rocking said eccentric, and a guide spool for the rod loosely mounted on said eccentric.

2. In a polishing machine, the combination 30 with a holder for the article to be polished, of a horizontally movable rod, a

holder for abrasive material pivoted to one end of said rod, said holder having arms projecting rearwardly at opposite sides of the rod, and springs interposed between said 35 arms and the rod.

3. In a polishing machine, the combination with a holder for the article to be polished, of a horizontally movable rod, a holder for abrasive material pivoted to one 40 end of said rod, said holder having arms projecting rearwardly at opposite sides of the rod, a bolt extending loosely through said rod and connected to said arms, and springs interposed between said arms and 45 the rod.

4. In a polishing machine, the combination with a holder for the article to be polished, of a horizontally movable rod, and a holder for abrasive material connected 50 to the rod, said holder having an opening adapted to receive a block of abrasive material, and means for clamping said block in the holder comprising a spring adapted to engage the block at its edges only. 55

In testimony whereof I affix my signature in presence of two witnesses.

JOHN J. HALDEMAN.
